UNITED STATES PATENT OFFICE

100,116

DESIGN FOR A VEHICLE TIRE

Arthur H. Nellen, Merion, and Frederick Leopold, Jr., Harmonville, Pa., assignors to Lee Rubber & Tire Corporation, Conshohocken, Pa., a corporation of New York

Application April 24, 1936, Serial No. 62,276

Term of patent 7 years

To all whom it may concern:

Be it known that we, Arthur H. Nellen and Frederick Leopold, Jr., both citizens of the United States, and residents, respectively, of Merion, county of Montgomery, State of Pennsylvania, and Harmonville, county of Montgomery, State of Pennsylvania, have invented a new, original, and ornamental Design for a Vehicle Tire, of which the following is a specification, reference being had to the accompanying drawing, forming a part thereof, wherein:

Figure 1 is a perspective view of a vehicle tire,

a section being illustrated in full lines and the complementary portion in dotted lines, showing our new design.

Figure 2 is a sectional view taken on the line 2—2 of Figure 1; and

Figure 3 is a fragmentary plan view of the tread surface of the tire.

We claim:

The ornamental design for a vehicle tire as shown.

ARTHUR H. NELLEN.
